JOSEPH S. WOOD, OF PLAINFIELD, NEW JERSEY.

Letters Patent No. 89,536, dated April 27, 1869.

IMPROVEMENT IN LAMPS.

The Schedule referred to in these Letters Patent and making part of the same.

To all whom it may concern:

Be it known that I, JOSEPH S. WOOD, of Plainfield, New Jersey, have invented a new and useful Improvement in "Atmospheric-Gas Lamps;" and I do hereby declare that the following is a full, clear, and exact description thereof, reference being had to the accompanying drawings, and to the letters of reference marked thereon.

The nature of my invention consists in the construction of lamps for burning hydrocarbon or other light oils.

These lamps are to be attached to ordinary gas-pipes in dwellings; also to railroad-cars or steamers.

An air-forcing apparatus is attached to the pipes, in some convenient position, and atmospheric air is forced through the absorbents in the said lamps. It thus becomes impregnated with hydrocarbon-vapor, and passes out at the burner.

The air, on its passage to the burner, previous to entering the absorbents, is heated by the flame from the burner.

To enable others skilled in the art to make and use my invention, I will proceed to describe its construction and operation.

Figure 1 is a general elevation of the whole arrangement.

Figure 2 is a section through the lamp.

Figure 3 is a perspective view of the burner.

Figure 4 is a section through the regulating-receiver.

Fig. 1 shows the blowing-apparatus, A, commonly used in carburetting air.

On its top is the pipe a', entering the water-tank B, fig. 4, containing an inverted receiver, C.

An interior pipe, c', with holes, c'', slides over the tube a'.

An arm, d, connects with the stop-cock d'', upon the gas-pipe E, and so, by the rising and falling of the receiver C, the pressure in the gas-pipes is regulated.

The gas-lamps G are screwed upon the gas-pipes, in the place of the usual burner.

The cock F is the same as that used for ordinary coal-gas, and is used for turning the gas on or off.

In fig. 2, G is the body of the lamp, in globe form, containing the absorbents S.

H is an inlet for gasoline, and closed by a screw-plug.

The stem K screws into the gas-pipe E.

The tube L divides into two branches, L and M.

The branch M is closed at the top, except a small opening, m, the opening of which is regulated by the thumb-screw n.

A tube, N, fits loose upon the tube M, leaving space for the carburetted air to pass between.

The top of this tube terminates in a burner, O.

The tube L passes upward, as shown, into the hollow flame-spreader P, and, down the opposite side,

L', into the body of the lamp, where it is perforated with holes, R, for the escape of atmospheric air.

The flame-spreader P is shaped as shown in fig. 3. It is hollow, for the passage of atmospheric air, and has an annular opening around the burner, for a current of fresh air to pass upward to the flame.

The operation of my apparatus is in this way:

The lamp G is filled with an absorbent material, S, and then with hydrocarbon. All that which is not absorbed is poured out again, and the inlet H closed.

This feature of the lamp makes it non-explosive.

The lamp is now screwed upon the gas-pipe E.

The blower A is set in motion, and pumps air along the pipes E, the force of the current being regulated by the receiver C acting upon the cock d'.

The cock F is turned, and air passes into the lamp G.

This air fills the pipe M, but the current passes up the tube L, into the flame-spreader P, which is heated by the jet of flame from the burner, and imparts its heat to the air passing through it.

The air descends in the tube L', and passes out through the openings R, and diffuses itself amongst the absorbent S, where it is impregnated with hydrocarbon-vapor, and then passes up, between the tubes M and N, to the burner O.

If the gas is too rich, the valve m is opened, and air from the adulterating-pipe M is allowed to mix with the gas.

This lamp can also be used upon a table of a parlor, air being conveyed from the pipe E by an elastic India-rubber tube.

This lamp will burn without the flame-spreader P and tube, but with this difference, that, with a pint of material, it will only burn three hours; and, if the air is heated with my hollow flame-spreader and tubes, the lamp will burn eight hours, and burn up all the material.

I do not claim forcing air, through gas-pipes, into self-generating-vapor lamps, as that has been previously done.

What I claim as my invention, and desire to secure by Letters Patent, is—

1. The lamp-body G, in combination with the tubes L M and flame-spreader P, for the purpose shown and described.

2. The combination of the globe G, containing an absorbent, S, with pipes L, M, and N, and burner O, arranged and operating substantially as described.

3. The adulterating-pipe M and valve m n, for the purpose shown and described.

4. Heating the impelled current of air, at or near the point of combustion, as it passes on its way, through the absorbent S, to the burner.

JOSEPH S. WOOD.
